His Attorney.

UNITED STATES PATENT OFFICE.

HENRY G. FRENCH, OF SCHENECTADY, NEW YORK, ASSIGNOR TO GENERAL ELECTRIC COMPANY, A CORPORATION OF NEW YORK.

PROTECTIVE DEVICE.

Application filed October 24, 1919. Serial No. 333,018.

To all whom it may concern:

Be it known that I, HENRY G. FRENCH, a citizen of the United States, residing at Schenectady, in the county of Schenectady, State of New York, have invented certain new and useful Improvements in Protective Devices, of which the following is a specification.

My invention relates to electrical protective devices, particularly to relays and has for its object to provide a novel and improved relay device which is operative in response to predetermined abnormal conditions to positively move into circuit controlling position, which is positively and definitely operative as soon as such abnormal conditions reach a predetermined amount, which is quickly returned to its initial position when such abnormal conditions disappear and which is in other particulars to be more specifically described, an improvement upon other relay devices heretofore known in the art.

The novel features which I believe to be characteristic of my invention will be definitely indicated in the claims appended hereto, while the features of construction and mode of operation will be understood by reference to the following description taken in connection with the accompanying drawings in which:

Fig. 1 shows, in perspective, a relay embodying my invention, Figs. 2 and 3 are perspective views showing modified forms of my invention, and Fig. 4 shows a detail of construction of the device shown in Fig. 2.

In Fig. 1 I have shown my invention applied to a relay of the induction type comprising a rotatable member or armature 1, preferably in the form of a thin flat circular disk of suitable non-magnetic conducting material and an electromagnetic driving or torque producing element 2 adapted to be connected to the circuit to be protected. Operatively related to the armature 1 is a retarding or magnetic drag element 3 which is shown as a permanent magnet. The armature 1 is carried by a shaft 4 upon which is mounted a contact member 5 adapted to move into and out of engagement with co-operating contacts 6 to control an auxiliary circuit and operate a trip coil or other suitable device. Operatively related to the shaft 4 is a restraining or spring element 7 adapted to exert a counter-torque on said

armature and rotate it in a direction opposed to that exerted by the torque or motor element 2.

Normally the force exerted by the counter torque or restraining element 7 is sufficient to overcome the torque exerted by the driving or torque producing element 2 and the armature is thus held in its initial position against a stop 8 or other suitable means. When, however, due to the occurrence of an abnormal condition above a predetermined amount on the circuit to be protected, the flux generated by the torque or current responsive element 2 is sufficient to exert a driving torque on the armature or rotatable member 1 of an amount necessary to overcome the counter torque exerted by the spring 7, the armature is moved in contact controlling direction and contacts 5 and 6 brought into engagement. As the armature 75 is rotated in contact controlling direction, the tension or countertorque exerted by the spring 7 is increased, requiring a correspondingly increased torque by the motor element 2 to compensate for the increase of 80 opposing or countertorque. If some compensation is not made for the increase in tension of the spring 7, a current just enough to start the armature in contact controlling direction would not be sufficient to 85 complete the movement of the armature to contact controlling position. Without an increase in current, therefore, the armature would come to rest with the torque and countertorque approximately balanced. 90 The increase in effect exerted by the countertorque element 7 may be compensated for in several different ways and according to my invention, I show three structures whereby this compensation is made and the 95 armature carried positively into contact controlling position by that torque which is sufficient to overcome the countertorque element and initially move the armature in contact controlling direction. Having a 100 positive movement of the armature 1 to contact controlling position insures the elimination of so-called "floating" caused by the armature starting from initial position and coming substantially to rest or floating at 105 some point intermediate initial and contact controlling position where the countertorque is substantially balanced by the driving torque. In this instance, a sudden increase in the abnormal condition would carry the 110

armature to tripping or contact closing position in a time interval which is quicker than desired, due to the smaller path of travel from floating to tripping position.

5 There is another feature to be overcome in relays of this type and that is a delay in return of the armature and contacts from tripping or contact controlling position to initial position. It is essential that the relay have a quick reset in order to be ready for the next operation. A slow reset would be open to the same disadvantage as the condition of "floating" as a second abnormal condition occurring before the armature 10 reaches initial position would carry the contacts to tripping position in a quicker time interval than desired.

I overcome all these objections by a structure which consists of a means to automatically increase the effect exerted by the motor element on the armature or one of its torque producing components to increase its torque to compensate for the increase in countertorque exerted by the spring or 15 countertorque element 7. In Fig. 1 this compensating means consists of a metallic or conducting member 9 preferably of a thin copper strip of a ring or close circuited configuration supported intermediate the upper 20 portion of the motor element 2 and the armature 1 which in this figure is shown in a position intermediate initial and contact controlling positions for more clearly illustrating the features of construction of the relay. 25 This member 9 is carried upon a suitable bearing device 10 and is movable into and out of the field produced by the driving element in response to the rotation of the armature. This function may be accomplished 30 by several structures, and by way of example, I have shown a gear wheel 11 carried by the shaft 4 and adapted to move the flux member 9 through a gear segment 12. With the armature 1 in normal or initial position, 35 the flux or close circuited member 9 is intermediate the pole tips of the upper portion of the torque element 2 and the armature 1 so that the magnetic flux passes through the central opening of the flux member 9. 40 When the effect of the motor element 2 predominates and the countertorque element is overcome initially to move the armature in contact closing direction, the rotation of the shaft 4 and gear wheel 11 moves the gear 45 segment 12 and gradually moves the close circuited member 9 across the field of the motor element 2. As the flux member 9 thus moves across and out of the field of the motor element, the flux member 9 acts as a 50 secondary or short circuited winding and varies the distribution and phase relations of the fluxes of the motor element 2. This results in an increase in the effective flux cutting the armature which gradually increases the torque exerted on the armature 55 60 65

by the motor element 2 to compensate for the increasing countertorque of the spring 7. That current therefore through the motor element necessary initially to overcome the countertorque of spring 7 and start the armature rotating in contact closing direction, is sufficient positively to carry the armature to contact closing position. Should, however, the current fall slightly below normal, the countertorque of the spring 7 predominates and starts to rotate the armature to initial position, returning at the same time the flux member 9 to initial position and decreasing the torque exerted by the motor element. This results in a decrease of driving torque with the consequent quick return of the armature and contacts to initial position.

In Fig. 2 is shown a slightly modified form of structure for compensating for the increase of countertorque. In this scheme the motor element 2 comprises an auxiliary winding 12' which is wound opposed to the main winding 13 and which is controlled through a flexible connection by contacts 14 and 15. These contacts are carried by an insulating support 16 which is adjustable to position the contacts in the path of travel of the moving contact 5. The contacts 14 and 15 may be normally open or closed but in the construction shown in Fig. 4 the contacts are normally open and held in the open position by the contact 5 which in initial position engages the lower end of contact 15. Contact 15 extends below contact 14 for this purpose and forms a stop for the movable contact. Both contacts are carried by spring members and are biased to engagement. As normally the effect of the countertorque element 7 predominates, the contact 5 is held in engagement with contact 15 and this contact held out of engagement with its cooperating contact 14. The circuit of auxiliary winding 12' is therefore maintained open.

When the current through the main winding of the motor element 2 increases, due to abnormal conditions, above a predetermined amount, the torque exerted by the motor element on the armature 1 is great enough to overcome the countertorque of spring 7 and the contact 5 is rotated in a direction to engage the operating contacts, not shown. The initial impulse or movement of the contact 5 releases auxiliary contact 15 which due to its bias, engages cooperating auxiliary contact 14. The engagement of contacts 14 and 15 closes the circuit of auxiliary winding 12' and it then functions as a closed circuited secondary relative to the main winding 13 of the motor element 2. The flux set up by winding 12' due to transformer action opposes the flux set up by main winding 13, and a resultant flux is set up which has an angle of displacement relative to the flux set up by the windings 17 in the lower portion of the motor element 2 such that

an increase in torque is exerted on the armature by the motor element which is sufficient to compensate for the increase in counter-torque exerted by spring 7. The armature 1 and contact 5 is positively carried into contact closing position without the objectionable feature of floating. A positive pick up of the armature is also obtained, that is the initial impulse necessary to start the 10 armature into operation is sufficient to positively move the armature to complete its path of movement. This scheme also operates on the principle of shifting the phase angle between the fluxes of the motor 15 element whereby the torque exerted thereby is increased to compensate for the increase in countertorque.

In Fig. 3 is shown a modified compensating structure which consists in providing 20 on the permanent drag magnets 3, extension pole tips 18 which are adjustably supported thereon. Cooperating with the pole tips 18 is an armature 19 mounted between the pole tips and rotatable in response to the shaft 25 4. The armature 19 is preferably mounted on the shaft 4 and is cam shaped in configuration. The relation of pole tips 18 and armature 19 is such that normally with the contact 5 in its initial position against the 30 stop 8, a large air gap exists between the armature 19 and each pole tip. As the armature 1 is rotated in response to the predominating effect of the driving torque, the rotation of shaft 4 rotates the armature 35 19 relative to the pole tips so that the gap between the armature 19 and each pole tip gradually decreases thus permitting more and more flux to traverse the armature 19 and hence exert a stronger and stronger 40 torque on the armature 19 to rotate the shaft 4 and armature 1 in contact closing direction. The increase in effective torque by the armature 19 and pole tips 18 added to the torque exerted by the motor element 2 45 is sufficient to compensate for the increase in countertorque exerted by spring 7. When the torque of the motor element falls off, the torque exerted on armature 19 likewise falls off so that the armature 1 is quickly returned to initial position.

What I claim as new and desire to secure by Letters Patent of the United States is:—

1. An induction relay comprising a rotatable armature, contacts controlled by the movement thereof, restraining means normally holding said armature in initial position, a motor element adapted to exert a torque on said armature tending to turn the same to contact controlling position operative in response to current in excess of a predetermined amount of overcome said restraining means, and means operative in response to a movement of said armature in contact controlling direction for varying the phase relations of the fluxes of said motor

element whereby the torque of the same is increased to compensate for the increase in restraining effect of said restraining means.

2. An induction relay comprising a rotatably mounted circular disk, contacts controlled by the movement thereof, restraining means for holding said disk in initial position, electromagnetic torque-producing means inductively associated with said disk operative in response to a current above a predetermined amount to overcome said restraining means and start said disk moving in contact controlling direction, and means affecting the torque exerted by said torque producing element whereby the current required to cause said torque producing means initially to overcome said restraining means is sufficient to complete the movement of said disk to contact controlling position.

3. An induction relay comprising a rotatable armature, contacts controlled by the movement thereof, an electromagnetic torque-producing element inductively associated with said armature and adapted to exert a torque thereon tending to turn the same in contact controlling direction, countertorque restraining means tending to turn said armature in the opposite direction normally effected to overcome the torque of said electromagnetic element and hold said armature in initial position, and a close circuited member movable by said armature across the field of said electromagnetic element to vary the phase relations of the fluxes thereof whereby upon movement of said armature the torque of said electromagnetic element is varied in accordance with the variation in torque of said countertorque restraining means.

4. An induction relay comprising a rotatable armature, contacts controlled by the movement thereof, restraining means normally holding said armature in initial position, a motor element adapted to exert a torque on said armature tending to turn the same to contact controlling position operative in response to a current in excess of a predetermined amount to overcome said restraining means, and means operative in response to the rotation of said armature for varying the phase relations of the fluxes of said motor element whereby the torque of the same is increased upon movement of said armature towards contact controlling position and decreased upon movement thereof towards the initial position.

5. An induction relay comprising a rotatably mounted disk, contacts controlled by the movement thereof, an electromagnetic element inductively associated with said disk and adapted to exert a torque thereon tending to move the same to contact controlling position, restraining means arranged to exert a countertorque on said disk normally effective to hold the same in

initial position and overcome by said electromagnetic element in response to currents therein in excess of a predetermined value, a rotatably mounted short circuited member 5 geared to said disk and movable thereby across the field of said electromagnetic element whereby upon movement of said disk toward contact controlling position the torque of the electromagnetic element is increased to compensate for the increase in countertorque of said restraining means.

6. An induction relay comprising a rotatably mounted circular disk, contacts controlled by the movement thereof, an electromagnetic element inductively associated with said disk and adapted to exert a torque thereon tending to turn the same to contact controlling position, a spring arranged to exert a countertorque on said disk normally 10 sufficient to overcome the torque exerted by

said electromagnetic element and hold the disk in initial position, the torque exerted by said spring being overcome by the torque of said electromagnetic element when energized by current above a predetermined amount to start said disk towards contact controlling position, and a rotatably mounted short circuited member movable across the field of said electromagnetic element between one of the poles thereof and said disk 20 in response to a movement of said armature whereby the torque of said electromagnetic element is caused to predominate and said disk is positively moved to contact controlling position in response to any current 25 above said predetermined amount.

In witness whereof, I have hereunto set my hand this 23rd day of October, 1919.

HENRY G. FRENCH.
